SHOE OR SIMILAR ARTICLE

Jacob B. Berland, Los Angeles, Calif., and Giuseppe Preti, Ferrara, Italy; said Preti assignor to said Berland

Application April 7, 1955, Serial No. 35,413

Term of patent 14 years

(Cl. D7—7)

We claim:

The ornamental design for a shoe or similar article, substantially as shown.
